UNITED STATES PATENT OFFICE.

HARRY BRENIZER, OF OMAHA, NEBRASKA.

ADJUSTABLE WINDOW-SHADE FIXTURE.

No. 889,294.

Specification of Letters Patent.

Patented June 2, 1908.

Application filed April 15, 1907. Serial No. 368,227.

To all whom it may concern:

Be it known that I, HARRY BRENIZER, a citizen of the United States, residing at Omaha, in the county of Douglas and State of Nebraska, have invented a certain new and useful Adjustable Window-Shade Fixture, of which the following is a specification.

This invention relates to improvements in adjustable window-shade fixtures.

10 The object of the present invention is to improve the construction of window-shade fixtures and to provide a simple, inexpensive and efficient device adapted to support a window-shade, also the lace curtains; and it 15 consists of the novel construction, combination, and arrangement of parts of which it is composed, whereby the window-shade may be vertically adjusted upon the said fixture and retained in any desired elevation for 20 ventilation or admission of light through the upper part of a window, all as will be herein-after described, and pointed out in the appended claims.

Referring to the accompanying drawings 25 forming a part of this specification and wherein like characters of reference denote similar parts throughout the several views:—

Figure 1, is an elevation of a curtain or window-shade fixture constructed in accordance 30 with my invention and shown applied to a window-frame. Fig. 2, is a side elevation thereof. Fig. 3, is an elevation in detail with portions of the fixture broken away showing the adjustable connection between 35 the sliding means thereof. Fig. 4, is a plan view of the adjustable connection with one end broken away. Fig. 5, is a side elevation in detail of one of the slides held in the guide. Fig. 6, is an elevation thereof. Fig. 7, is a 40 plan view showing one end of a window-shade or shade-roller and a curtain pole mounted on the bracket end of the slide, the slide being shown as held by the vertical guide.

45 Referring to the drawings, 1, designates the vertical guides which are secured to the opposite sides of a window-frame, and constructed of suitable metal, and receiving the vertical movable slides 2, which carry a curtain or shade 3, and a curtain pole 4 and which are adapted to permit the curtain to be arranged at any elevation for the purpose of ventilation and to arrange the light as desired. The vertical guides are each provided 50 with the vertical flanges 5, and the openings

6, arranged at intervals and forming shoulders to be engaged by the tooth 7 of the slides, as clearly shown in Fig. 5, of the drawings, whereby the slides are locked at desired adjustment. It will be observed that the slides 2 are each reduced in width as at 8 and are curled at their lower end to form a handle 9 and that the tooth 7 is formed by slitting the reduced end 8 as clearly shown in Figs. 5 and 6. The slides being reduced as at 8 forms the edges 10 which work in the ways 11 of the guides 1. The upper end of the slides are twisted or given a half turn as clearly shown in Figs. 5 and 6 to form a bracket 12 which is provided with the slot 13 for the reception of the journals of an ordinary spring-roller which carries the curtain or shade 3, and further provided with the C shaped end 4 for carrying the ends of a curtain pole.

75 To adjust the slides the operator simply grasps the handle 9 pulls the reduced end outward which disengages the tooth 7 from the shoulder of the opening 6 which allows the slides to be readily adjusted.

The adjustable suspended connection or brake A, consists of two arms or bars 15 provided with the slots 16 and held together by means of the bolt 17 which is provided with the thumb nut or bur 18. These arms are 80 each provided with the heads 19 having the slot 20 thus allowing them to fit over the brackets 12 of the slides 2, which prevents the slides from sliding one way or the other independent of one another consequently 85 keeping the spring-roller and curtain or shade from falling out of the bracket 12 when moving the slides in adjusting the same.

Having fully described my invention, what 90 I claim is:—

1. A device of the class described comprising guides having ways and a plurality of openings secured to opposite sides of a window frame, slides mounted in said guides 100 having their upper ends provided with a half turn to form supporting brackets and their lower ends reduced to form a handle and provided with a tooth to engage in said openings, and adjustable means connecting said 105 brackets.

2. A device of the class described comprising guides secured to opposite sides of a window-frame, slides having their upper ends provided with a half turn to form brackets 110

adapted to support a shade-roller and curtain pole and an adjustable means connecting said brackets.

3. A device of the class described comprising guides provided with a plurality of openings and secured to opposite sides of a window-frame and running the full length thereof, slides mounted in said guides having their lower ends reduced and provided with a tooth adapted to work in said openings, and

an adjustable means having connection with said slides.

In testimony whereof I have signed my name to the specification in the presence of two subscribing witnesses.

HARRY BRENIZER.
